UNITED STATES PATENT OFFICE.

LEO JNO. BAYER, OF ST. LOUIS, MISSOURI, ASSIGNOR TO BAYER STEAM SOOT BLOWER COMPANY, OF ST. LOUIS, MISSOURI, A CORPORATION OF MISSOURI.

BOILER-CLEANER.

1,028,083.

Specification of Letters Patent.

Patented May 28, 1912.

Application filed November 11, 1911. Serial No. 659,797.

To all whom it may concern:

Be it known that I, LEO JOHN BAYER, citizen of the United States, residing at St. Louis, State of Missouri, have invented certain new and useful Improvements in Boiler-Cleaners, of which the following is a full, clear, and exact description, reference being had to the accompanying drawings, forming a part hereof.

10 My invention has relation to improvements in boiler cleaners; and it consists in the novel features of construction more fully set forth in the specification and pointed out in the claims.

15 In the drawings, Figure 1 is a side elevation of a water-tube boiler showing my invention applied thereto, part of the furnace wall being broken away; Fig. 2 is a vertical cross-section through the side wall 20 of the furnace taken on the line 2—2 of Fig. 1; Fig. 3 is a similar sectional view enlarged, of the upper portion of the illustration in Fig. 2; Fig. 4 is a combined section and front elevation of the upper portion of the 25 hollow sectional standard through which the steam nozzles operate; Fig. 5 is a side view of Fig. 4; Fig. 6 is a top plan of said hollow standard; Fig. 7 is an enlarged horizontal section through the side wall of the 30 furnace on the broken line 7—7 of Fig. 1; Fig. 8 is a front end view of the boiler showing the header nozzles in position; Fig. 9 is a perspective (broken away) of the 35 nozzle installation for the header, detached; Fig. 10 is a longitudinal sectional detail showing one of the side nozzles closed by a perforated plug for projecting jets to assist the draft; Fig. 11 is a cross-section on the line 11—11 of Fig. 10; Fig. 12 is a front 40 sectional elevation of a modified form of nozzle-supporting standard; and Fig. 13 is a side elevation of the same.

The object of my invention is to provide a cleaner or soot-blower for water-tube 45 boilers having the combined characteristics of the Heine and Babcock & Wilcox type, that is to say, boilers having a shell and a water-tube section in which the latter is baffled transversely, and wherein either or 50 both water-legs (or headers) are provided with hollow stay-bolts opposite the spaces between the tubes. This type of boiler (the Edge-Moor being an example) requires the 55 installation of a blower system partaking of features identified with systems of both the

Heine and Babcock & Wilcox boilers, said features being so disposed as to work cooperatively to accomplish the object in view, that is to say to not only dislodge the soot, dirt, ashes and other accumulations on the 60 water-tubes (and shell) but to carry the material so dislodged out of the boiler-furnace in the general direction of the draft of the boiler.

A further object is to provide means for 65 manipulating the movable nozzles by which the transverse projection of the cleaning fluid (steam) is accomplished, such means being particularly adapted to work in conjunction with the nozzle supports as at present installed in this class of boilers.

A further object is to provide other structural features the advantages of which will be fully apparent from a detailed description of the invention which is as follows:—

Referring to the drawings and for the present to Figs. 1 to 9 inclusive, F represents the furnace (the walls being broken away in parts) of a well known type of 80 water-tube boiler (Edge-Moor), S representing the shell of the boiler, and T the water-tubes. As well understood in the art the water-tube portion is divided off into independent intercommunicating sections by 85 transversely disposed baffle-plates *a* traversed by the tubes, the general draft being rearward and upward from the fire-box F. In the present example two such baffle-plates and three sections are shown though such 90 number may vary in practice. Disposed along one of the side walls of the furnace opposite the middle section (in the present example) is a vertical opening O tapering inwardly (Fig. 7) there being located at 95 the line of convergence of the vertical tapering side walls of said opening, a hollow standard or tube 1 provided with series of off-sets or shoulders *s*. Between each pair of offsets is confined a hollow rotatable cylinder 2 which is free to rock about the axis of the tube 1, there being one such cylinder opposite a space between two superposed series of tubes T. To insert the cylinders (or bearings) 2 into the tube 1, the latter 100 must necessarily be made of (at least) two sections separable along a vertical plane, the upper and lower ends of the respective sections having cast with them the anchors or shoes 3 set in the brick work of the fur- 105 110

section adjacent such leg and a set of nozzles 4 installed as quite obvious, as otherwise no means would be present to blow this section. To assist the draft in such 5 section it is clear that the uppermost nozzle 4 of the series would be provided with a plug 11 in which the passages r would be turned up so as to carry the products over the first baffle a .

10 The arrangement of the hollow standard 1 with its series of bearings 2 is not the only method of supporting the nozzles 4 leading from the movable riser 5; and in Figs. 12 and 13 I show a modification in the form 15 of an outer tubular standard 1' of uniform cross-section provided with an inner tube 2' through which the nozzles may pass. In that case as in the first form the member 1' is provided with transverse slots m' for the 20 free play of the nozzles, the pipe 2' being previously inserted into the tube 1'. In this modification the member 1' need not be made sectional. Like the first form the standard 1' is provided with anchor arms or 25 shoes 3' by which it may be secured to the furnace wall.

The operation, readily understood from the foregoing may be summarized as follows:—To clean or "blow" the boiler the 30 operator opens the necessary valves V whereupon the nozzles 8 will project the steam jets in the spaces between the tubes in a general direction parallel with the tubes, the nozzles 4 on the other hand projecting the jets between the tubes but in a 35 general direction transverse or at an angle to the tubes. To reach every available portion of the boiler section dependent on the nozzles 4, the operator seizes and moves the 40 handle or lever 6, thereby causing the riser 5 to sweep about the common axis of the nozzles 4, the latter oscillating about the axis of the hollow standard 1. As stated above, any section of the boiler may be 45 cleaned independently of another section, or all the sections may be blown simultaneously. It may be stated in passing that in the event the rear water-leg had no hollow stay-bolts, it would be necessary to install a riser 5 with its nozzles 4 to blow the 50 section adjacent this leg.

Having described my invention, what I claim is:—

1. In combination with a boiler having a 55 water-tube section composed of series of tubes disposed in superposed planes, and spaced apart, terminal headers communicating with said tubes, transverse baffles for the tubes, a series of nozzles disposed over 60 the tube area at one end of the water-tubes for projecting a cleaning fluid longitudinally with the tubes into the spaces between the tubes, series of nozzles for projecting a 65 cleaning fluid transversely across the boiler into the spaces between the tubes, the

mingled fluids and the dirt dislodged thereby following the general direction of the draft whereby the same are expelled from the furnace of the boiler.

2. In combination with a boiler having 70 a water-tube section composed of series of tubes disposed in superposed planes, and spaced apart, terminal headers communicating with said tubes, transverse baffles traversed by the tubes whereby the boiler 75 is divided into inter-communicating sections, nozzles mounted over the tube area in one of the headers opposite the spaces between the tubes for projecting jets of cleaning fluid into said spaces in a direction 80 lengthwise with the tubes, movable nozzles positioned opposite a section between two consecutive baffles for projecting a cleaning fluid into the spaces between the tubes in a direction transverse of the boiler, the 85 intensity of the respective currents being regulated to cause the resultant current to follow the general direction of the draft and carry the dirt out of the furnace of the 90 boiler.

3. In combination with a boiler having a water-tube section composed of series of tubes disposed in superposed planes, and spaced apart, terminal headers communicating with said tubes, transverse baffles 95 traversed by the tubes whereby the boiler is divided into intercommunicating sections, nozzles mounted over the tube area in one of the headers opposite the spaces between the tubes for projecting jets of cleaning fluid 100 into said spaces in a direction lengthwise with the tubes, nozzles oscillating about and disposed across a fixed axis positioned opposite a section between two consecutive baffles, a riser adapted to sweep about said axis and 105 coupled to the nozzles, and means for supplying a cleaning fluid under pressure to said riser and nozzles.

4. In combination with a boiler having a water-tube section baffled transversely, 110 whereby the same is divided into sections, means distributed over the tube area at the ends of the tubes for projecting a cleaning fluid longitudinally with the tubes into a portion of the sections and transversely into 115 another portion of the sections.

5. In combination with a boiler having a water-tube section composed of series of tubes disposed in superposed planes and spaced apart, terminal headers communicating with said tubes, transverse baffles traversed by said tubes whereby the boiler is divided into intercommunicating sections, nozzles mounted over the tube area in one of the headers opposite the spaces between the tubes for projecting jets of cleaning fluid into said spaces in a direction lengthwise with the tubes, nozzles oscillating about and disposed across a fixed vertical axis positioned opposite a section between two con- 125 130

secutive baffles, a riser to which said nozzles are coupled, adapted to sweep in a circle concentric with said axis, and means for supplying cleaning fluid under pressure to 5 said riser.

6. In combination with a boiler having a water-tube section composed of series of tubes disposed in superposed planes and spaced apart, terminal headers communicating with said tubes, transverse baffles traversed by said tubes whereby the boiler is divided into inter-communicating sections, nozzles mounted over the tube area in one of the headers opposite the spaces between the 10 tubes for projecting jets of cleaning fluid into said spaces in a general direction lengthwise with the tubes, nozzles oscillating about and disposed across a fixed vertical axis opposite a section between two consecutive baffles, a riser, a hollow swiveled joint coupled to the base of said riser and provided with a section oscillating about the axis of oscillation of the nozzles, the outer ends of the nozzles being secured to the riser, the parts 15 operating substantially as set forth.

7. In combination with a boiler having a water-tube section composed of series of tubes disposed in superposed planes and spaced apart, terminal headers communicating with said tubes, transverse baffles traversed by said tubes whereby the boiler is divided into inter-communicating sections, nozzles mounted over the tube areas in the headers opposite the spaces between the 20 tubes for projecting jets of steam into said spaces in a general direction lengthwise with the tubes, nozzles oscillating about and disposed across a fixed vertical axis opposite a section between two consecutive baffles, a vertical riser, a hollow swiveled joint at the base of the riser provided with a section oscillating in an arc concentric with the axis of oscillation of the nozzles, the outer ends of the several nozzles being secured to said 25

riser, and means for supplying steam to the 45 riser and nozzles.

8. In combination with a boiler having a water-tube section composed of series of tubes disposed in superposed planes and spaced apart, terminal headers communicating 50 with said tubes, transverse baffles for the tubes dividing the boiler into intercommunicating sections, means distributed over the tube area of one of the headers for projecting a cleaning fluid through said header 55 into the spaces between the tubes in a general direction parallel to the tubes, and means for projecting a cleaning fluid into one or more of the boiler sections into the spaces between the tubes in a general direction 60 transverse to the tubes.

9. In combination with a boiler having a water-tube portion baffled transversely and divided into intercommunicating sections, means distributed over the tube area at one 65 end of the tubes for blowing a section in a general direction parallel to the tubes, and means for blowing a section in a general direction transverse or at an angle to the tubes.

10. In combination with a boiler having a water-tube portion baffled transversely and divided into intercommunicating sections, means distributed over the tube area at one 70 end of the tubes for blowing a section in a general direction parallel to the tubes, means for blowing a section in a general direction transverse or at an angle to the tubes, and means identified with the transverse blowing 75 means to drive the dislodged dirt in the general direction of the draft.

In testimony whereof I affix my signature, in presence of two witnesses.

LEO JNO. BAYER.
